Patented May 29, 1923.

Des. 62,435

UNITED STATES PATENT OFFICE.

WILLIAM SCOTT, JR., OF NORRISTOWN, PENNSYLVANIA.

DESIGN FOR A STOCKING.

Application filed June 21, 1921. Serial No. 479,399. Term of patent 7 years.

To all whom it may concern:

Be it known that I, WILLIAM SCOTT, Jr., a citizen of the United States, residing at Norristown, in the county of Montgomery and State of Pennsylvania, have invented a new, original, and ornamental Design for Stockings, of which the following is a specification, reference being had to the accompanying drawing, forming part thereof, in which:

Figure 1 is a rear elevation of the stocking, showing the design as it will appear when the stocking is being worn; and

Figure 2 is a side view of the foot of a stocking having the design shown in Figure 1.

The essential feature of my design is a heel having relatively large, well defined "steps" on both of its sides as shown in the drawing.

I claim:

The ornamental design for a stocking, as shown and described.

In testimony whereof I affix my signature.

WM. SCOTT, JR.
